UNITED STATES PATENT OFFICE.

ADOLPH L. DE LEEUW, OF CINCINNATI, OHIO, ASSIGNOR TO THE CINCINNATI MILLING MACHINE COMPANY, OF CINCINNATI, OHIO, A CORPORATION OF OHIO.

TOOTH-REST.

1,071,634.

Specification of Letters Patent. Patented Aug. 26, 1913.

Application filed May 27, 1913. Serial No. 770,170.

To all whom it may concern:

Be it known that I, ADOLPH L. DE LEEUW, a citizen of the United States, and residing at Cincinnati, in the county of Hamilton and State of Ohio, have invented a new and Improved Tooth-Rest, of which the following specification is a full disclosure.

This invention relates to a means instrumental in enabling milling cutters to be brought to the action of a grinding wheel in such a way that each tooth will be ground in an identical manner so that each will be of equal efficiency when subsequently used for milling work.

15 One object within the contemplation of this invention is to render available a mechanically simple and operatively superior attachment in the nature of a "tooth rest" applicable to various machine tools for enabling the teeth of any desired form of cutter successively to be brought gradually to the action of a grinding wheel whereby the cutter may be so sharpened that all of its teeth will act with equal efficiency.

25 Another object is to devise a universal tooth rest having a non-resilient blade capable of forming a solid support for the cutter, yet adapted to swivel out of the way with all the freedom of a resilient blade 30 and then back gradually into its normal position.

Other objects will be in part obvious from the annexed drawings and in part indicated in connection therewith by the following analysis of this invention.

This invention accordingly consists in the features of construction, combination of parts and in the unique relations of the members and in the relative proportioning 40 and disposition thereof; all as more completely outlined herein.

To enable others skilled in the art so fully to comprehend the underlying features thereof that they may embody the 45 same by the numerous modifications in structure and relation contemplated by this invention, drawings depicting a preferred form have been annexed as a part of this disclosure, and in such drawings, like characters of reference denote corresponding parts throughout all the views, of which:

Figure 1 is a plan view of this attachment. Fig. 2 is a side elevation partly in section along line 2—2 of Fig. 1. Fig. 3 is 50 a section through line 3—3 of Fig. 1. Fig.

4 is a detail showing how the first arm is secured to the slotted arm.

The tooth rest proposed by this invention is a considerable departure from the principles heretofore utilized in such devices. That is to say, instead of employing a flexible blade having its shank rigidly fastened to the supporting arm or member, this invention utilizes a rigid blade having a pivotal mount on the arm and resiliently 60 spring-pressed into a normal relation therewith whereby it may yield to permit of the passage of a tooth.

The proposed structure obviates certain inaccuracies fundamentally inherent in old 70 style devices since the tooth rest always will impact each tooth at an invariable distance from the axis of the cutter (which is not always the case with spring blades by reason of their vibration) and furthermore, 75 in my device a given tooth will always occupy the same station in point of revolution since my rigid blade provides no spring or yield save during the passage of the tooth. This attachment is fully shown by 80 the drawings, in which 1 indicates an arm having a slot 2 adapted to receive a bolt 4 whereby it may be adjustably secured in any desired relation to a grinder, as for example, to the bed thereof. This arm 1 85 preferably has its top and bottom faces planed in parallelism and near one end it is apertured to receive a bolt 5 taking into a swivel block 6 that is in turn transversely apertured and is telescoped by the collar 7. 90

This block 6 preferably has its axis arranged at right angles to the length of the slotted arm or member 1, and it receives a second arm 8 having a smooth cylindrical shank extending at right angles to the block 6, so that by loosening the nut 5 the arm 8 may be rotated about its own axis with respect to the block 6 or translated axially into any desired relation with said block 6, and at the same time the block 6 100 may swivel about its axis perpendicular to the slotted arm 1. This enables the second arm 8 to take up any desired position whatsoever in a plane parallel with that of the first arm 1. A third arm 9 has a cylindrical shank arranged transversely to the second arm and passing through an 105 aperture in the head 10 of said arm, whereupon it is adjustably secured by means of a finger screw 11. The arm 9, thus being 110

- translatable and rotatably carried by the second arm 8, is capable of being given any position in space relative to the slotted arm 1 so that its head 12 may be brought into any desired relation with the cutter. Pivoted in this head 12 is a blade preferably having an offset tooth rest portion 13, providing the open aperture 14 whereby the tooth rest portion has the shown bifurcated form. A stop 15 determines the normal position of the blade 13 and by means of a suitable spring this blade is resiliently maintained in this normal position.
- 15 In use, the attachment is adjusted so that the slotted end of the blade squarely contacts with the advance or radial face of the tooth of the cutter so as to then positively determine the relation of such tooth to the grinder. After the grinder has passed over the relieved contour of the tooth, the cutter is rotated to bring the next tooth into position, the blade swinging aside during the passage, and such next tooth is 20 then brought firmly against the blade and then ground, and so on.
- Having thus revealed my invention, I claim as new and desire to secure by Letters Patent of the United States:—
- 25 1. A tooth rest of the nature disclosed combining a slotted arm adapted to be mounted on a machine tool and having a block transversely pivoted to one end thereof, a second arm translatable and rotatably mounted on said block at right angles there-

with, a third arm translatable and rotatably carried by said second arm at right angles therewith, a tooth supporting blade pivoted to the end of said third arm and spring-pressed in one direction thereon, and 40 a stop determining the normal position of said blade.

2. A tooth rest of the nature disclosed combining a member adapted to be adjustably attached to a machine tool, an arm 45 having a pivot-retaining head, a thin non-resilient blade pivoted in said head and having its free end adapted to position a tooth, a stop limiting the movement of said blade about said pivot, a spring normally 50 maintaining said blade against said stop and a universal supporting connection between said arm and said member.

3. A tooth rest of the nature disclosed combining a member adapted to be adjustably attached to a machine tool, an arm, a tooth rest blade pivoted on said arm and having a bifurcated extremity, means resiliently normally maintaining said blade in definite relation with said arm, and a 55 universal supporting connection adjustably mounting said arm on said member.

In witness whereof, I hereunto subscribe my name, as attested by the two subscribing witnesses.

ADOLPH L. DE LEEUW.
